UNITED STATES PATENT OFFICE.

JAMES A. MEBANE, OF SOUTH BOSTON, VIRGINIA.

DESIGN FOR A SOCKET FOR INCANDESCENT ELECTRIC LAMPS.

No. 38,484.

Specification for Design.

Patented March 19, 1907.

Application filed February 11, 1907. Serial No. 356,937. Term of patent 7 years.

To all whom it may concern:

Be it known that I, JAMES A. MEBANE, a citizen of the United States, residing at South Boston, in the county of Halifax and State of Virginia, have invented a new and original Design for the Sockets of Incandescent Electric Lamps, of which the following is a specification, reference being had to the accompanying drawing, forming part there-

of, and which represents a perspective view of my design.

I claim—

The ornamental design for a socket for incandescent electric lamps, as shown.

JAMES A. MEBANE.
